FOLDING BACK REST FOR SOFA BEDS

James Piliero, Astoria, N. Y., assignor to The
Englander Company, Inc., Chicago, Ill., a cor-
poration of Delaware

Application April 28, 1951, Serial No. 223,525

3 Claims. (Cl. 5—59)

1

This invention relates to a sofa bed having a back rest for supporting the back of a person disposed in seated position on the sofa bed and which is movable to an out-of-the-way position for use of the sofa bed as a double bed.

An object of the invention is to provide a mounting means for the back rest by which the same is supported in operative position over the mattress of the sofa bed and by which the back rest may be conveniently moved to the out-of-the-way position when the sofa bed is to be used as a bed.

Still another object of the invention is to provide mounting means which has limit positions for disposing the back rest in the operative and out-of-the-way positions respectively and which is connected with the back rest so as to rigidly support the same when the sofa bed is in use as a couch.

Still another object of the invention is the provision of mounting means for connecting the back rest to the back of the sofa bed which eliminates the necessity of providing ledges for supporting and guiding the movement of the back rest to the out-of-the-way position.

Still another object of the invention is to provide a mounting means which retains the back rest in the out-of-the-way position and which eliminates the possibility of unintentional or accidental forward movement of the back rest which might injure an occupant of the sofa bed.

With the foregoing and other objects in view, reference is now made to the following specification and accompanying drawings in which the preferred embodiment of the invention is illustrated.

In the drawings:

Fig. 1 is a perspective view of a sofa bed provided with a back rest and mounting means therefor constructed in accordance with the invention.

Fig. 2 is an enlarged transverse sectional view taken at one end of the sofa bed and showing the back rest in operative position.

Fig. 3 is a similar view of a fragmentary portion of the sofa bed showing the back rest moved to the out-of-the-way position.

Fig. 4 is a fragmentary sectional view taken approximately on line 4—4 of Fig. 2.

Referring to the drawings by characters of reference, the sofa bed includes a furniture frame 10 which may be of any desired construction and which as illustrated includes a rear wall 11, opposite end walls 12 and 13 and a mattress 14 arranged between the end walls 12 and 13 and

2

which is of a width to serve as a double bed. The sofa bed also includes a back rest 15 which is adapted to be arranged in forwardly disposed inclined relation for use of the sofa bed as a couch.

In order to rigidly support the back rest in forwardly inclined relation and to permit of the convenient movement thereof to an out-of-the-way position when the sofa bed is to be used as a bed, the back rest is hingedly connected along its upper edge as at 16 to a top wall 17 which latter wall is hingedly connected along its rear edge as at 18 to the upper end of the rear wall 11 for swinging movement of the back rest 15 and top wall 17 to dispose the same in substantially close parallel relation above the rear wall 11. A mounting means 20 is provided at each end of the back rest which has limit positions for disposing the back rest in the forwardly disposed inclined position over the mattress and in the out-of-the-way position above the rear wall and which provides a firm support for the back rest when in the forwardly inclined position and prevents the possibility of unintentional or accidental forward movement of the back rest from the out-of-the-way position to thereby avoid any possibility of injuring an occupant of the sofa bed.

Each of the mounting means 20 includes a link 21 which is pivotally connected at its forward end to the back rest 15 by means of a U-shaped cleat 22 and at its opposite end the said link is pivotally connected on a pivot pin 23 to a bracket 24 affixed at its upper end to an angle bar 25. A link 26 is pivotally connected to the link 21 intermediate its ends on a pivot pin 27 and at its lower end the said link is connected with the angle bar 25 for limited guiding movement by means of a headed stud 28 slidably engaging in a vertical slot 29 in the forwardly projecting flange 30 of said angle bar. The cleats 22 are pivotally connected with the links 21 by pivot pins 31 and are secured over the ends of the back rest 15 and the angle bars 25 affixed to the forward face of the rear wall 11 adjacent the end walls 12 and 13. It will be understood that the headed studs 28 which slidably connect the links 26 with the angle brackets 25 abut against the bottom of the slots to provide a limit position for supporting the back rest in forwardly inclined position over the mattress when the sofa bed is used as a couch. The said studs are adapted to abut against the upper ends of said slots to provide a limit position for disposing the back rest in the out-of-the-way position above the rear wall 11 and when in such position the

links 26 prevent unintentional movement of the back rest to the forwardly inclined position.

Constructed in this manner, a sofa bed is provided which may be used as a double bed or as a couch and which provides a convenient compartment 33 at the rear of the back rest 15 for storing bed clothes and the like when the sofa bed is used as a couch.

The mattress 14 may be supported in any desired manner such as by a box spring indicated generally by the reference character 33 disposed upon the bottom panel 34 of the furniture frame 10.

What is claimed is:

1. In a sofa bed of the type adapted to be used as a couch or as a bed, a body including a rear wall and opposite end walls connected with the rear wall adapted for receiving a mattress disposed between said end walls, a back rest, a top wall hingedly connected with the rear wall along the upper edge thereof and hingedly connected with the back rest along its upper edge, and a mounting means at each end of said back rest having limit positions for disposing and supporting said back rest in forwardly inclined relation over the mattress for use of the sofa bed as a couch and for disposing the back rest in an out-of-the-way position above the rear wall in parallel relation with the top wall for use of the sofa bed as a bed, each of said mounting means including a vertically disposed support affixed to the rear wall at one end thereof and having a forwardly projecting flange provided with a vertically disposed slot, a link pivoted to said back rest and to the upper end of said support, and a link pivoted to said first mentioned link intermediate the ends thereof and having a head at its lower end slidably arranged in said slot and adapted to abut against the lower end of said slot to provide the limit position for the mounting means disposing and supporting the back rest in the forwardly inclined position and said head being adapted to abut against the upper end of said slot to provide the other limit position for disposing the back rest in the out-of-the-way position.

2. In a sofa bed of the type adapted to be used as a couch or as a bed, a body including a rear wall and opposite end walls connected with the rear wall adapted for receiving a mattress disposed between said end walls, a back rest, a top wall hingedly connected with the rear wall along the upper edge thereof and hingedly connected with the back rest along its upper edge, and a mounting means at each end of said back rest for

supporting said back rest in a forwardly inclined relation over the mattress for use of the sofa bed as a couch and for supporting the back rest for swinging movement to an out-of-the-way position above the rear wall in parallel relation with the top wall for use of the sofa bed as a bed, each of said mounting means including a vertically disposed support affixed to the rear wall at one end thereof and having a forwardly projecting flange provided with a vertically disposed slot, a link pivoted to said back rest and to the upper end of said support and a link pivoted to said first mentioned link intermediate the ends thereof and having a head at its lower ends slidably arranged in said slot for permitting swinging movement of the first mentioned link about the pivotal connection with the support for disposing the back rest in said forwardly inclined relation and in said out-of-the-way position.

3. In a sofa bed of the type adapted to be used as a couch or as a bed, a body including a rear wall and opposite end walls connected with the rear wall adapted for receiving a mattress disposed between said end walls, a back rest, a top wall hingedly connected with the rear wall along the upper edge thereof and hingedly connected with the back rest along its upper edge, vertically disposed supports affixed to the rear wall at the opposite ends thereof and having forwardly projecting flanges provided with vertically disposed slots, links pivoted to said back rest and to the upper ends of said supports respectively, and links pivoted to said first mentioned links intermediate the ends thereof and having heads at their lower ends slidably arranged in the slots of said forwardly projecting flanges respectively for permitting swinging movement of the first mentioned links about the pivotal connections with the supports for disposing the back rest in a forwardly inclined relation and in an out-of-the-way position.

JAMES PILIERO.
